SYSTEM OF RADIO TELEPHONY AND
TELEGRAPHY

Herbert S. Polin, San Francisco, Calif., assignor,
by direct and mesne assignments, to Interna-
tional Radiophone Corporation, Washington,
D. C., a corporation of Delaware

Application October 31, 1929, Serial No. 403,717

18 Claims. (Cl. 250—9)

This invention relates to improvements in high frequency telephone transmitting and receiving systems and apparatus.

In accordance with a principal feature the invention provides a system for transmitting and receiving signals wherein each station comprises synchronously tuned vacuum tube transmitter and receiver units adapted to oscillate at a common carrier frequency in synchronism with each other and with the corresponding units of other stations, whereby two-way intercommunication between stations may be effected on the common carrier frequency.

An important aspect of the invention is that at a given station one antenna is operatively associated with both the transmitter and the receiver. That is to say, the transmitter and the receiver use the same aerial and the same ground. The transmitting unit and the receiving unit are coupled preferably both inductively and directly to the antenna circuit.

A very important feature of the invention is that the transmitter and receiver at a given station are so connected that each functions regeneratively to amplify the signal in transmitting as well as in receiving. That is to say, on transmitting a wave or signal generated by the transmitter is impressed on the associated receiver, and regeneratively amplified by it as well as by the transmitter, in consequence of which the transmitted or departing wave represents a summation of the combined regenerative amplifying action of the transmitter and receiver. Similarly, on receiving a wave or signal impressed on the receiver is also impressed on the associated transmitter, and regeneratively amplified by the transmitter as well as by the receiver, so that the wave or signal as received and detected represents a summation of the combined regenerative amplifying action of the transmitter and of the receiver. This cooperative interaction just described between transmitter and receiver is achieved in part by virtue of the mentioned direct and inductive coupling of both transmitter and receiver to the common antenna.

An important feature of the antenna circuit is that it is provided with a wave conductor tuning unit, which acts as a micrometric wave filter, and allows the passage, in either direction, only of waves having a very definite and accurately predetermined frequency, and no other waves. This wave conductor-tuning-unit may be in the form of a solenoidal coil which is finely or micro-metrically adjusted and tuned to allow the pas-

sage of energy of the desired frequency, and no others.

The transmitting unit at the one station has exactly the same characteristics as the transmitting unit at the other station, and the receiving unit at the one station has exactly the same characteristics as the receiving unit at the other station. At each station, the transmitting and receiving units, are, as stated, synchronously tuned with respect to each other as well as synchronously in tune with their counterparts at the opposing station. The tuning elements in the antenna at the respective stations are accurately tuned to pass waves of the same predetermined frequency only. Both stations, therefore, transmit and receive on a common carrier frequency, and none other. There is thus set up between stations a field of radiant energy of this same frequency, and all the tubes at both stations are caused thereby to oscillate in synchronism at this frequency.

To describe further the regenerative amplification of a signal wave at a given station:—On receiving, incoming modulated carrier wave signals impinging on the antenna are simultaneously impressed on the associated transmitter and receiver units thereat, in such manner that each regeneratively amplifies the portion of the signal energy applied thereto. Due to the mentioned direct connection and inductive coupling between units to the common antenna circuit, the transmitting and receiving portions react upon one another at both the carrier and modulating frequencies further to intensify or amplify the signals. The signals ultimately detected thus embody a summation of the individual regenerative amplifying effects of the transmitter and receiver units, together with their cooperative amplifying action. Likewise on transmitting, the modulated wave created in the transmitter portion is regeneratively amplified thereby, and also independently as well as cooperatively by the associated receiver unit as a result of the inductive and direct couplings between units operative at both the carrier and modulating frequencies. The ultimate wave thus radiated from the antenna accordingly comprises a summation of these several amplifying effects.

This regeneration of the incoming waves by the operation of the transmitting unit at the receiving station enables the receiving station effectively to receive relatively much weaker signals than otherwise with consequent increase in range of reception. Another obvious result is

that less power need be used at the opposing transmitting station for a given range.

Certain circuit features of the present invention are disclosed in my copending application 5 Serial Number 364,838, filed May 21, 1929.

For the purpose of illustration, the figure on the drawing shows two stations A and B, station A having a transmitter T and receiver R, and station B having a transmitter T' and receiver 10 R'.

Referring now to transmitter portion T of station A, the antenna 1 is connected to solenoidal coil 2, adjustably mounted with respect to the metal plate 3; this plate is connected to one terminal of coil 4, the other terminal of which is conducted to ground 17. The elements 2 and 3 are relatively adjustable and act as a wave conductor tuning unit achieving a resonance tuning and serving as a micrometric wave filter, which 20 will allow the passage, in either direction, of waves of only a definite pre-determined frequency, and no other waves. The coil 4 is inductively coupled to coil 5.

25 A screen grid tube 6, has its plate 7, connected by conductor 8, to one terminal of coil 5, the other terminal of which is connected to the positive terminal of the high voltage power source 9, by conductor 10. Tapped from an intermediate potential point of the high voltage power source 30 9, is conductor 11, the other terminal of which is connected to the screen grid 12, of tube 6.

Grid 13 is connected by conductor 14 to one terminal of the crystal oscillator 15, the other terminal of which is connected by conductor 16 35 to ground 17. Another conductor 18, leads from grid 13 through choke 19 and grid leak resistance 20 to one terminal of the output winding 21 of a transformer or induction coil the other end of which goes to ground 17. This transformer 40 has a core 22 and a primary coil 23. A microphone of any desired type 24, in series with a suitable power source 25, is interposed in this primary circuit as shown.

The cathode 26, of the screen grid tube 6 is 45 provided with a suitable energizing means 27 and is connected through conductor 30 to ground. A condenser 28 is interposed between cathode 23 and conductor 11, as shown. A circuit comprising conductor 8, variable condenser 29 and conductor 14, forms a shunt between the grid 13 and plate 7, as shown.

The receiving unit R of station A is also inductively coupled to the antenna circuit comprising antenna 1, solenoidal coil 2 and metal plate 3, 50 by conductor 31 which is connected to one terminal of coil 32 the other terminal of which is grounded at 17.

A screen grid tube 34 which comprises a grid 35, screen grid 36, cathode 37 and plate 38, has 60 its cathode provided with suitable energizing means 39 and is connected through conductor 40 to ground 17. A condenser, 41, is interposed between cathode 37 and conductor 42 as shown. A circuit comprising conductor 43, condenser 45 65 and conductor 44 forms a shunt between the plate 38 and grid 35 of tube 34 as shown. The screen grid 36 is connected through conductor 42 to an intermediate potential point of a source of power 46. The plate circuit of this 70 tube comprises a source of power 46, the negative terminal of which is connected to ground 17 through ear phones 47 and conductor 48. The positive terminal of said power source 46 is connected through coil 49 and conductor 44 to plate 75 38.

The grid 35 of this tube is connected by conductor 43 and coil 33 (which is inductively coupled to coil 32) to the negative side of a power source 50, the positive terminal of which is grounded at 17. This power source furnishes a 5 negative bias to grid 35 of tube 34.

The transmitter unit and the receiver unit are also directly connected by conductors 30, 31 and 43, so that incoming or outgoing signals are impressed on and amplified by both units, whereby 10 during transmission T and R act as transmitters, and during reception T and R act as receivers.

Station B is a substantial duplicate of station A; each station operates in the same way in sending and receiving; and corresponding parts 15 are indicated by primed reference characters.

The operation of the circuit as shown in the illustration is as follows: Upon the closing of all 20 circuits oscillations will initiate in the circuits of the tubes 6 and 34 which may have a fundamental frequency predetermined by the characteristics of crystal 15. These oscillations, taking character from the voice impressed upon the microphone 24, will be impressed upon the grid of tube 6. This tube will amplify said oscillations and impress these said amplified oscillations on the output coil 5 which is inductively coupled to antenna coil 4. The impressed wave will be conducted through coil 4 and inductively passed to wave conductor coil 2 through plate 3 30 to antenna 1 and thence into space.

Simultaneously the modulating frequencies originating in the microphone 24 are applied directly to the grid of receiver tube 34 over the circuit comprising direct connections 30-31-48 35 and the inductive coupling between coils 32 and 33, and thus modulate the high frequency oscillations generated by the receiver. Also the modulated high frequency oscillations originating in the transmitter T are applied through inductive couplings 5-4 and 32-33 and the common antenna circuit, to the receiver R to be regeneratively amplified thereby. The resulting amplified signals of the receiver are thereupon fed back into the antenna system and radiated therefrom.

The energy producing these oscillations is derived from a source of current here shown as a battery, although it will be understood that this showing is purely diagrammatic and any suitable source of power may be employed.

It will further be understood that, while for convenience of illustration, various distinct sources of current are shown, in practice, many or all of these may be combined so that all power is derived from a single source.

Throughout the two stations, an exceedingly fine tuning of identical apparatus, each to the other, has placed these stations in synchronous adjustment and the insertion of resonance tuning makes for an additional micromatic filter in an already super selective circuit. In operation, there is set up between the two antennas, a band of radiant energy of a predetermined accurate frequency and all units of the two stations are placed in absolute synchronism. I have found that the action of the opposing stations, under this new arrangement of transmitting and receiving units, permits intercommunication without the necessity of making inoperative the whole or any portion of the transmitting or receiving units during intercommunication between the two stations.

The high selectivity of this circuit which is resonance tuned and the synchronization 75:

achieved by the exact tuning of the individual portions of the apparatus make for the absorption and elimination of all types of interference. The pre-determined frequency channel is open 5 to its synchronously operated station and it alone, permitting secrecy of operation on this band.

The two transmitters and the two receivers are designed to oscillate in synchronism. This is assured by suitable adjustments of the tuning 10 elements, and by constructing the crystal controls for the several stations to have like characteristics. The transmitting and receiving units at each station are so closely interconnected, being connected directly and inductively as has 15 been described, as to maintain syntony of oscillation therein despite possible slight differences or maladjustment of tuned frequencies for the transmitting and receiving units respectively. In other words, the coupling between transmitting 20 and receiving units is such that they will pull into step and maintain a common oscillation frequency.

Another new and unusual result of operation with this circuit is its operative efficiency for 25 radio phone communication on an extremely low wave length and at a frequency heretofore assumed to be impractical for this purpose.

An incoming wave is received in the receiver R in the usual way. However, since the transmitter T, as well as the receiver R is inductively and 30 directly coupled to the same antenna circuit, an important new result is attained, in that the same incoming wave impresses its character on the transmitter T and is amplified and regenerated by this transmitter and fed back into coils 5 and 4 and thence into coils 32 and 33, and thence into the receiver R, thereby strengthening, regenerating and amplifying the energy received by 35 the station, thereby achieving effective reception of weaker signals than would otherwise be possible, and whereby less power need be used at the transmitting station to maintain effective communication with its opposing station.

This unit combination, as described, has for 40 an additional purpose, the provision of a valve or filter in any transmitting or receiving circuit. Inserted in the antenna circuit between the aerial and coupling of standard transmitter, and/or receiving units, it permits the passage only of 45 energy of pre-determined frequency.

While for purposes of illustration and simplicity, two tubes are shown in the drawing which 50 illustrates a simple receiving and transmitting circuit, it is readily understood that if and when functioning as a valve, the unit is operative, both for transmitting and receiving, with but one tube as part of the unit. This unit maintains synchronous relation with its counterpart at the opposing station. That is to say, the functions 55 of transmitting and receiving described for the two tubes, can be performed by a single tube acting as an appurtenance to the receiving and transmitting circuit.

It should be understood that the invention disclosed can equally well be used in radio telegraphy, in which case, a telegraphic key could be used in place of the microphone circuit.

The invention has been disclosed only diagrammatically and in its present preferred form. 60 It should be understood that the disclosure is illustrative, and not restrictive of the invention, and that the inventive concept may be carried out in various other ways, as falling within the 65 scope of the appended claims.

I claim as my invention:—

1. A combined radio telephone transmitting and receiving apparatus, comprising in combination a transmitting unit and a receiving unit, an antenna inductively coupled to both units, and means directly connecting both units to the antenna, whereby incoming waves are impressed upon both units, the waves impressed upon the transmitting unit being fed inductively back into the receiving unit, whereby the waves are thus 5 regenerated and amplified.

2. A combined radio telephone transmitting and receiving apparatus, comprising in combination synchronously tuned transmitting and receiving units, an antenna common to both units, a wave conductor tuning unit interposed in the antenna circuit, whereby incoming waves are impressed upon both units, the waves impressed upon the transmitting unit being fed inductively back into the receiving unit, whereby the waves are thus 10 regenerated and amplified.

3. A combined radio telephone transmitting and receiving apparatus, comprising in combination a transmitting unit, a receiving unit, a conductor directly connected and inductively coupled to both units, a resonance tuning unit interposed in the conductor circuit, whereby incoming waves are impressed upon both units, the waves impressed upon the transmitting unit being fed inductively back into the receiving unit, whereby the waves are thus 15 regenerated and amplified.

4. A combined radio telephone transmitting and receiving apparatus, comprising in combination a transmitting unit, a receiving unit, an antenna directly connected and inductively coupled to both units, a wave conductor tuning unit interposed in the antenna circuit, the tuning unit serving to filter the waves passing through it and to permit the passage only of waves of a 20 definite frequency, whereby incoming waves are impressed upon both units, the waves impressed upon the transmitting unit being fed inductively back into the receiving unit, whereby the waves are thus 25 regenerated and amplified.

4. A combined radio telephone transmitting and receiving apparatus, comprising in combination a transmitting unit, a receiving unit, an antenna directly connected and inductively coupled to both units, a wave conductor tuning unit interposed in the antenna circuit, the tuning unit serving to filter the waves passing through it and to permit the passage only of waves of a 30 definite frequency, whereby incoming waves are impressed upon both units, the waves impressed upon the transmitting unit being fed inductively back into the receiving unit, whereby the waves are thus 35 regenerated and amplified.

5. A radio telephone system which comprises a combined transmitter unit and receiver unit, said units being tuned synchronously, and means directly connecting the units to each other so that a received signal is amplified not only by the receiver unit but also by the transmitter unit associated therewith.

6. A radio telephone system for transmitting and receiving signals which comprises a combined transmitter unit and receiver unit, said units being adapted to oscillate in synchronism with each other, and means inter-connecting the two units whereby a portion of a received signal is picked up by the transmitter and impressed on the receiver.

7. A radio telephone system for transmitting and receiving signals which comprises a combined transmitter unit and receiver unit, said units being adapted to oscillate in synchronism with each other, and means inter-connecting the two units whereby a portion of a received signal is picked up by the transmitter and amplified, the signal thus amplified being impressed on the receiver.

8. A radio telephone system for transmitting and receiving signals which comprises a transmitter unit and receiver unit adapted to oscillate in synchronism with each other and means for directly connecting and inductively coupling the transmitter unit to the receiver unit so that dur- 70 75

ing operation both units cooperate in the reception of signals.

9. A radio telephone system for transmitting and receiving signals which comprises a combined transmitter unit and receiver unit, said

- 5 units being adapted to oscillate in synchronism with each other, means for directly connecting said units to each other so that at least a portion of the received signal is regenerated and amplified by the transmitter unit and impressed on the receiver unit and means for inductively coupling the transmitter unit to the receiver unit so that during operation both units cooperate in the reception of signals.
- 10

- 15 10. A radio telephone system for transmitting and receiving signals which comprises a combined transmitter unit and receiver unit, said units being adapted to oscillate in synchronism with each other, means for directly connecting and inductively coupling the transmitter unit to the receiver unit so that an impressed signal is regenerated and amplified by the transmitter unit, the signal thus regenerated and amplified being impressed on the associated receiver unit, and thus added to the same signal as is amplified by the receiver unit.
- 20
- 25

- 30 11. A radio telephone system for transmitting and receiving signals which comprises a combined transmitter unit and receiver unit, said units being adapted to oscillate in synchronism with each other, means for connecting the said units whereby a received signal is regenerated and amplified by the transmitter unit and the signal thus received and amplified is inductively and directly impressed upon the receiver unit, and so is added to the said received signal amplified by the receiver unit.
- 35

- 40 12. A radio telephone system for transmitting and receiving signals which comprises a combined transmitter unit and receiver unit, said units being adapted to oscillate in synchronism with each other, an antenna directly connected to the said units and means for inductively coupling the transmitter unit and the receiver unit to the common antenna.
- 45

- 45 13. A radio telephone system for transmitting and receiving signals which comprises a combined transmitter unit and receiver unit adapted to oscillate in synchronism with each other, means

for directly connecting the said units to each other so that at least a portion of a received signal is regenerated and amplified by the transmitter unit and impressed on the receiver unit, an antenna for the said units, and means for directly and inductively coupling the said units to the said antenna.

14. A radio telephone system for transmitting and receiving signals which comprises a combined transmitter unit and receiver unit adapted to oscillate in synchronism with each other, an antenna connecting the transmitter unit to the receiver unit so that during reception a portion of a received signal is picked up by the transmitter and impressed on the receiver.

15 15. A radio telephone system for transmitting and receiving signals which comprises a plurality of stations, each station having a transmitter unit and a receiver unit all adapted to oscillate in synchronism with each other, means for directly connecting the units of each station to each other so that at least a portion of a received signal is regenerated and amplified by the transmitter unit of the receiving station and is impressed on the receiver unit thereof, each station of the system capable of adjustment to synchronism with other stations thereof.

16. High frequency signaling apparatus comprising in combination, a regenerative signal transmitting device, a regenerative signal receiving device, and means so coupling said devices that each regenerates the signal of the other.

17. High frequency signaling apparatus comprising in combination, a regenerative signal transmitting device, a regenerative signal receiving device, and means so coupling said devices to a common antenna that each regenerates the signals of the other whereby said devices cooperatively amplify transmitted and received signals.

18. A duplex radio system comprising a crystal controlled oscillating transmitter unit, an oscillating receiver unit, and coupling means therebetween adapting said units to oscillate in synchronism, whereby the crystal control of the transmitter controls the oscillating frequency of the receiver.

HERBERT S. POLIN.
